UNITED STATES PATENT OFFICE

163,339

AUTOMOBILE

Houston Thompson, Milwaukee, Wis.

Application November 21, 1949, Serial No. 6,162

Term of patent 7 years

(Cl. D14—3)

To all whom it may concern:

Be it known that I, Houston Thompson, a citizen of the United States, residing at 1246 N. 7th St., Milwaukee, in the county of Milwaukee, and State of Wisconsin, have invented a new, original, and ornamental Design for an Automobile, of which the following is a specification, reference being had to the accompanying drawing, forming part thereof.

Figure 1 is a side elevational view of an automobile showing my new design;

Figure 2 is a front elevational view;

Figure 3 is a top plan view thereof, and

Figure 4 is a rear end elevational view of the same.

I claim:

The ornamental design for an automobile, as shown.

HOUSTON THOMPSON.
